[57] CLAIM

The ornamental design for a body for a doll, as shown and described.

DESCRIPTION

FIG. 1 is a front and right side perspective view of a body for a doll showing my new design;

FIG. 2 is a front elevational view thereof;

FIG. 3 is a right side elevational view thereof;

FIG. 4 is a left side elevational view thereof;

FIG. 5 is a rear elevational view thereof; and,

FIG. 6 is a top plan view thereof.

The bottom of the boots that are not shown in the drawings are flat and unornamented. The broken lines showing a doll head and hands in FIGS. 1 through 5 are for illustrative purposes only and do not form part of the claimed design.
